WORK SUPPORT

Keith F. Gallimore and Everett K. Morgan, Fond du Lac, Wis., assignors to Giddings & Lewis Machine Tool Co., Fond du Lac, Wis., a corporation of Wisconsin

Application November 23, 1942, Serial No. 466,558

25 Claims. (Cl. 90—56)

The invention relates to an improved work support for heavy duty machine tools, particularly suitable for use with horizontal boring, drilling and milling machines.

One object of the invention is to provide a work support of the above general character, embodying in a single unitary structure, a table or the like operative to hold a large heavy workpiece in position to be operated on by the tool together with power means operable selectively to translate the entire supporting structure and the work toward or from the tool or to rotate the table and work about a horizontal axis at either a rapid traverse rate or at a slower variable feed rate.

Another object is to provide an improved rotary work support adapted for use with horizontal boring, drilling and milling machines of either the table type or floor type.

Another object is to provide novel means for supporting the peripheral edge of a rotatable work table to effectually prevent the deflection of the table under load.

Still another object is to provide clamping means of novel and improved construction adapted for use with rotatable or translatable machine elements and operative to positively clamp the movable elements to the machine frame.

A further object resides in the construction and arrangement of the frame work, table, driving mechanism and other elements of the work supporting structure to adapt it for use with extremely large workpieces and for what is commonly known as heavy duty service.

Other objects and advantages of the invention will become apparent from the following detailed description of the preferred embodiment illustrated in the accompanying drawings, in which:

Figure 1 is a side elevational view of a work support embodying the features of the invention.

Fig. 2 is a front elevational view of the work support.

Fig. 3 is a plan view of the work support.

Fig. 4 is a fragmentary sectional view taken in a horizontal plane through the axis of the table supporting spindle substantially along the line of 4—4 of Fig. 2.

Fig. 5 is a vertical sectional view taken along the line 5—5 of Fig. 2.

Fig. 6 is a diagrammatic view of the drive mechanism.

Fig. 7 is a horizontal sectional view taken

along the line 7—7 of Fig. 2 showing the drive mechanism in plan.

Fig. 8 is a diagrammatic view of the hydraulic control and lubricating systems.

5 Fig. 9 is a sectional view of the clamping mechanism taken along the line 9—9 of Fig. 10 with parts broken away to show details of construction.

Fig. 10 is a plan view of the clamping mechanism taken in a horizontal plane substantially on the line 10—10 of Fig. 2.

Fig. 11 is an end view of one of the table supporting devices taken in a plane substantially on the line 11—11 of Fig. 2.

15 Fig. 12 is a sectional view taken on the line 12—12 of Fig. 11.

Fig. 13 is a side view of the table supporting device taken in a plane substantially on the line 13—13 of Fig. 11.

30 Fig. 18 is an end view of the table feed reduction mechanism taken in a vertical plane substantially on the line 18—18 of Fig. 7.

Fig. 19 is a vertical sectional view taken along the line 19—19 of Fig. 18.

Fig. 20 is a developed sectional view of the hand feed mechanism for the rotary table.

Fig. 21 is a fragmentary vertical sectional view taken along the line 21—21 of Fig. 1.

40 While the invention is susceptible of various modifications and alternative constructions, we have shown in the drawings and will herein describe in detail the preferred embodiment, but it is to be understood that we do not thereby intend to limit the invention to the specific form disclosed, but intend to cover all modifications, adaptations and alternative constructions falling within the spirit and scope of the invention as defined in the appended claims.

50 For purposes of exemplification, the improved work support comprising the present invention has been shown in the form most suitable for use with heavy duty horizontal boring, drilling and milling machines. Referring to Figs. 1, 2 and 3 of the drawings, the work support, as herein

shown, comprises a carriage or saddle 30 adapted to be slidably supported on horizontal ways 31 formed on the upper face of an elongated base or bed 32. The bed may be a part of an existing table type horizontal boring, drilling and milling machine or it may be supplied especially for the work support if desired. The bed, as shown, is of box type construction and is provided with three of the ways 31. Bolted or otherwise rigidly secured to the bed, inside the two outer ways, are a pair of inwardly facing racks 33, utilized in traversing the saddle on the ways, as will appear presently.

Rising from the saddle 30 is a column-like structure including a sub-base 35, a base 36 and a frame 37 mounted one above the other and all rigidly bolted together. The column structure is provided at its upper end with bearings for a horizontal spindle 39 (Figs. 4 and 5) which supports a rotary work table 40. The table supporting spindle is disposed with its axis parallel to the longitudinal axis of the bed and with the table facing the end of the bed adjacent which a tool supporting structure is conventionally located.

In the exemplary machine, the saddle 30 is constructed in the form of a heavily ribbed casting generally rectangular in horizontal section and having its lower surface machined to form bearings for engagement with the ways 31. The saddle is held securely on the ways by locking plates 43 carried on flanges 41 depending from opposite side edges of the saddle. Parallel depending ribs 42 on the underside of the saddle cooperate with vertical guide surfaces formed on opposite sides of the center way to guide the saddle in its reciprocation on the ways. Suitable gib plates 42' may be provided as required for adjusting purposes.

As will be seen by reference to Figs. 5 and 7 of the drawings, the sub-base 35 is in the form of a box-like casting generally rectangular in horizontal section and having an outwardly projecting flange 44 by which it may be bolted to the saddle 30. The sub-base is provided with internal ribs or webs 45 to make it sturdy and rigid, such ribs being suitably arranged to provide space for the reception of the various units of the drive mechanism to be described hereinafter. Openings in the side walls of the sub-base provide convenient access to the drive units, such openings being provided with sheet metal covers 46.

The base 36 (Fig. 5) is likewise a heavily ribbed, box-like rectangular casting and is provided at its lower edge with a flange for bolting it to the sub-base 35. The frame 37 rises from the front edge of the base 36 and comprises a central section 47 (Fig. 5) having spaced bearing seats 48 and 49 for supporting the table spindle 39. A semi-circular flange 50 integral with the section 47 serves to enclose the rear portion of the table 40.

Referring to Figs. 4 and 5, the table supporting spindle 39 is formed at one end with a cylindrical pilot 51 engageable in a central recess in the table 40 to accurately locate the table on the spindle. An integral flange 52 is provided at the base of the pilot for bolting the table to the spindle. The spindle is mounted for rotation in large tapered roller bearings, three such bearings 53, 54 and 55 being provided in the present instance. The bearing 53 is mounted in the front bearing seat 49 of the frame section 47 as close to the table as practicable. The intermediate bearing 54 is mounted in the rear bearing seat 48 of

the frame section and is spaced rearwardly from the front bearing so as to hold the spindle rigidly against lateral movement.

The bearings 53 and 54 are arranged in opposed relation and the latter is provided with adjusting mechanism by which both bearings may be preloaded. This mechanism may be of any suitable and well-known type and as herein shown comprises a ring 56 encircling the spindle and having a plurality of screw-threaded members 57 projecting from one side to engage the inner race ring of the bearing 54. Movement of the ring 56 rearwardly of the spindle is blocked by a removable abutment in the form of a split ring 58 engaging in a peripheral groove in the spindle. The spindle and bearings may thus be forced into tight preloaded engagement by screwing in the threaded members 57.

The rear bearing 55 provides additional support for the spindle at the end remote from the table. As herein shown, this bearing is of the opposed roller type and is provided with adjusting mechanism 59 similar to that above described. The bearing is supported in a bracket 60 bolted to the top of the base 36. A housing 61 encloses the bearing bracket and the end of the spindle projecting beyond the intermediate bearing 54.

The table 40 is preferably in the form of a heavily ribbed casting, circular in contour, and recessed centrally for the reception of the spindle pilot 51. Inset from the periphery of the table is an integral, rearwardly projecting flange 62 to which is bolted or otherwise rigidly secured an annular worm wheel 63 adapted to be driven by a cone-type worm 64 (Figs. 4 and 6) fast on a vertical shaft 65 extending upwardly from the sub-base 35 as shown in Fig. 2. Intermediate the periphery of the table and the flange 62 is mounted a hardened steel ring 66 (Figs. 4, 5, 9 and 11-13) formed with outwardly facing teeth 67 adapted to cooperate with clamping means to be described hereinafter. The face of the table is formed with transverse parallel T-slots 68 for securing the work to the table.

Means is provided for positively clamping the table 40 to the machine frame to hold it securely in fixed position while a tool is operating on a workpiece. This means, as herein shown, comprises a clamping plate 70 (Figs. 5, 9 and 10) having one side edge formed with relatively fine rack teeth 71 adapted to mesh with the teeth 67 of the locking ring 66 secured to the table. The clamping plate is slidably supported and guided in a housing comprising a bottom plate 72 having upstanding flanges 73 along each side edge to which a cover plate 74 is suitably secured. The housing is rigidly anchored to the base 36 with the locking plate in position for cooperation with the teeth of the ring 66.

The clamping plate is yieldably urged outwardly from the housing, that is, toward the locking ring in any suitable manner. As herein shown, the means provided for this purpose comprises a pair of cylindrical plungers 75 seated in recesses in a pad 76 upstanding from the bottom plate of the housing. Each plunger is provided at its outer end with a roller 77 engageable with the rear edge of the clamping plate and coiled compression springs 78 acting on the inner ends of the plungers serve to force the rollers against the plate. A spring pressed plunger 79 located between the two plate shifting plungers engages in a recess in the edge of the clamping

plate to maintain it in centered position with respect to the first mentioned plungers.

The clamping plate is shifted to and held in a withdrawn position against the action of the plungers 75 by an eccentric or cam 80 integral with a rock shaft 81 journaled in the bottom and cover plates of the housing and extending through an aperture in the locking plate. The cam coacts with a forwardly facing surface 82 defined by the aperture to retract the locking plate when the shaft 81 is rocked into the position shown in Fig. 9. As the shaft is rocked out of that position, the cam is withdrawn from the surface 82, thus permitting the clamping plate to shift forwardly under the influence of the plungers 75 and thereby engage the rack teeth 71 with the teeth of the ring 66.

Means is provided for accurately centering the clamping plate in its advanced or operated position and for positively clamping it in a position to preclude any rotative movement of the work table. This means, as herein shown, comprises a pair of wedge members 83 slidably supported in the housing with the clamping plate and on opposite sides thereof for cooperation with the side edges of the plate which are tapered gradually from front to rear as shown in Fig. 9. The wedge members are guided for movement toward and from the ring 66 by ribs 84 (Fig. 10) engaging in complementary grooves 85 in the bottom plate 72. The arrangement is such that the wedge members upon moving forwardly engage opposite side edges of the clamping plate and positively hold it in forward or operated position to which it was initially shifted by the plungers 75.

The operation of the wedge members is coordinated with the release and retraction of the clamping plate by the cam 80 by utilizing this cam for shifting the wedge members. To this end the cam is seated in a closely fitting recess in a cross member or link 86 arranged to extend over the outer faces of the clamping plate and the wedge members as shown in Figs. 9 and 10. The cover plate 74 serves to maintain the link in position in the housing. Pins 87 projecting from the inner side of the link engage in transverse slots 88 in the respective wedge members to provide an operative connection between the link and the members. Due to this pin-and-slot connection, the link is free to move in an arcuate path defined by the cam 80 in response to rocking of the cam shaft. The forward and rearward increments of such movements are imparted to the wedge members to shift them into or out of clamping position.

While any suitable means may be utilized to rock the cam shaft 81 for clamping and releasing the table, it is desirable to employ power actuated means, preferably pressure fluid operated, for this purpose because of the severe strains to which the table is subjected in heavy duty service. The actuating means, as herein shown, comprises a piston 90 (Figs. 8-10) working in a cylinder 91 bolted or otherwise secured to one side of the clamping plate housing. The piston is fitted with a rod 92 extending transversely across the housing at one side of the cam shaft. Rack teeth 93 formed on the piston rod engage the teeth of the pinion 94 fast on the cam shaft. With this arrangement positive locking of the table is obtained by the wedging action of the members 83 on the plate 70 which effectually prevents disengagement of the plate by reason of the strains imposed on the table.

Clamping mechanism similar in all respects to that above described, is also provided on the saddle for positively clamping that machine part in fixed position on the ways. In this instance the locking plate 10 is positioned to engage a rack 95 fixed to the side wall of the machine bed 32 as shown in Figs. 1 and 2. The elements of the saddle clamping mechanism are identified by the same reference characters as the corresponding elements of the table clamping mechanism with the additions of the suffix *a*.

Novel means is provided for supporting the work table adjacent its periphery to counteract any tendency for the table to deflect under load. 15 As the tool is ordinarily applied to the work at a point below the axis of the table spindle, the supporting means is associated with the lower portion of the table. This supporting means, as shown in Figs. 1, 2 and 11 to 13, comprises a plurality of adjustable supporting devices 100 mounted on the machine base 36 and arranged to bear against a suitable track carried on the inner side of the table. The track, in this instance, is formed by the outer surface of the hardened ring 66 previously described. As the supporting devices are alike in construction, a description of one will be sufficient.

Referring now to Figs. 11-13, the supporting device 100, in its preferred form, comprises a block or shoe 101 of bronze or other suitable material having a flat bearing surface 102 adapted to engage the face of the ring 66. The shoe is supported by needle bearings on an eccentric 103 formed on a shaft 104 which in turn is supported at opposite sides of the eccentric in needle bearings 105 and 106 carried by a bracket 107 secured to the machine base.

Splined to the forward end of the shaft 104 is a crank arm 108 having its tip portion bifurcated to straddle a bolt 109. A nut 110 threaded on the end of the bolt is formed with a convex surface adapted to engage a complementary concave surface on the crank arm. The bolt 109 is disposed transversely of the shaft 104 and is slidably supported in an aperture in a lug 111 projecting laterally from one side of the bracket 107. A coiled compression spring interposed between the lug and a cup-shaped cap member 113 abutting the head of the bolt urges it outwardly or to the right as viewed in Figs. 11 and 13. Through the connection provided by the nut 110 and crank arm 108, the shaft 104 is thus rocked in a direction to force the shoe 101 against the rear face of the ring 66. The pressure exerted by the shoe on the ring may be regulated as required for any particular work by simply turning the bolt in the nut 110 so as to vary the tension of the spring 112.

The general form and arrangement of the novel drive mechanism provided by the invention may be readily seen by reference to Fig. 6 of the drawings in which the relationship between the various elements is shown diagrammatically. It may be noted, at this time, that the drive mechanism is built up of a plurality of separate structural units which materially simplifies manufacture and initial assembly of the machine and which greatly facilitates removal of the parts for repair or replacement.

70 Due to the weight of the parts to be moved in a work supporting structure of the type under construction, it has been found desirable to utilize separate electric motors M and M' (Figs. 6 and 7) for effecting such movements at rapid traverse and slow feed rates respectively. The

motor M may be of the reversible type to adapt it for driving the parts in either direction. Motor M' may be of the unidirectional type with reversal of the drive effected through a suitable transmission. A feed and rapid traverse selector unit A is provided for connecting these motors selectively with a main drive shaft 120. In the exemplary machine, a heavy duty multiple disc clutch 121 (see also Fig. 14) is provided for connecting up the rapid traverse motor while a positively acting clutch 122 performs this function for the slow feed. The clutches are adapted to be engaged selectively or to be set to neutral position by remote control through the medium of pressure fluid operated clutch actuating mechanism shown in Figs. 8 and 14 of the drawings and described hereinafter.

As the rapid traverse drive is used primarily for making rough positioning adjustments of the work, a single traverse rate is satisfactory. The slow feed drive, however, is employed for fine adjustment where a high degree of accuracy is required, and it is therefore desirable to provide for varying the slow feed rate over a relatively wide range. The slow feed drive is, therefore, taken through a variable speed hydraulic transmission H which is driven from the motor M', in this instance, by a multiple V-belt drive 123. The transmission H may be of any suitable and well known type and is desirably provided with a reversing and speed regulating motor RM so that the necessary adjustments may be effected by remote control.

Means is also provided whereby the main drive shaft 120 may be coupled selectively with suitable driving mechanism for rotating the table 40 or for driving the saddle 30 along the machine bed. To this end the drive shaft 120 is arranged to drive an intermediate shaft 124 forming a part of a feed selector unit B. This drive is effected through a worm 125 on the main shaft and a worm wheel 126 on the intermediate shaft.

The selector unit includes a pair of mechanically interconnected clutches 127 and 128 (see also Figs. 15 and 16) operable to connect the shaft 124 with either of two axially aligned shafts 129 and 130. The clutches are adapted to be shifted to their respective engaged positions or to a neutral position by a fluid actuator shown in Figs. 8 and 15 and described hereinafter. The shaft 129 through bevel gears 131 and 132 drives a horizontal shaft 133 leading to a speed reducing unit C (Figs. 6, 7, 18 and 19) which, in turn, drives the vertical shaft 65 carrying the table driving worm 64.

The shaft 130 is drivingly connected through gears 134 and 135 (Figs. 6 and 16) with a saddle drive shaft 136 having removably coupled sections 137 and 138 drivingly coupled with vertical shafts 139 (Figs. 6 and 17) disposed at opposite sides of the saddle. The vertical shafts carry pinions 140 meshing with the racks 33 on the machine bed. The drive for each vertical shaft 139 includes a worm 141 fast on the associated shaft sections 137 and 138 cooperating with a worm wheel 142 fast on the pinion shaft.

In addition to the power drive means above described, auxiliary drive units D and E are provided for driving the table and saddle by hand. The auxiliary unit D (see Fig. 20) for driving the table is coupled with the speed reducing unit C by a shaft 145. The unit D includes intermeshing gears 146, 147, 148 and 149 of which gear 146 is fixed to the shaft 145 and gears 147 and 148 are fast on a common shaft 150. Gear 148 is

fast on a shaft 151 which carries a suitable indicator or dial 152 for indicating the degree of movement imparted to the table. A clutch gear 153 fixed on an axially slid able shaft 154 is adapted to be shifted into or out of mesh with the gear 149. The shaft 154 is turned by a hand crank 155 having clutch teeth engaging complementary teeth 156 at one end of a sleeve member 157 fixed to the shaft and projecting at one side of the saddle. A spring 158 acting on the sleeve 157 yieldably urges the shaft and gear 153 to the disengaged position shown in Fig. 20 but permits engagement of the gear 153 with gear 149 when the table is to be driven manually. The various gear shafts above mentioned are journaled in a housing 159 adapted to be secured to the side of the sub-base 35.

The hand drive unit E for the saddle is similar to the unit D except that it has a smaller speed reduction ratio. As shown diagrammatically in Fig. 6, a shaft 160 (see also Figs. 15 and 16) coupled with the shaft 130 extends to the unit and is provided with a gear 161 meshing with a pinion 162 on a shaft 163. Also fast on the shaft 163 is a gear 164 and an indicator or dial 165 adapted to indicate the degree of movement imparted to the saddle. A clutch gear 166 fast on an axially slid able shaft 167 is adapted to be moved into or out of mesh with the gear 164. Shaft 167 is turned by a hand crank 168 through a clutch connection similar to that above described.

It will be apparent from the foregoing that the entire work supporting structure may be traversed along the machine bed at either a rapid traverse rate or at a selected slow feed rate as desired by suitable manipulation of the clutches 121, 122 and 128. Alternatively, the table 40 may be rotated at a rapid traverse rate or at a selected slow feed rate by appropriate manipulation of the clutches 121, 122 and 127. Moreover, these movable machine parts may be driven manually independently of the power drive mechanism when desired.

Reference may now be had to Figs. 14-20 of the drawings for a more detailed disclosure of the power drive mechanism. Thus, as shown in Fig. 14, the rapid traverse and feed selector unit A comprises a generally rectangular housing 160 adapted to be rigidly secured to the top of the saddle 30 within the sub-base 35. Supported in the housing on spaced anti-friction bearings is a short shaft 161 having on its outer end a coupling member 162 adapted to cooperate with a companion member 163 on the shaft 164 of the rapid traverse motor M. The other end of the shaft 161 is formed with an enlarged cup-shaped head 165 which constitutes the driving member of the clutch 121.

Alined axially with the shaft 161 is a sectional shaft 166. One end of the latter shaft is supported in a bearing 167 seated in a counter bore in the adjacent end of the shaft 161. The opposite end of the shaft 166 projects through the side wall of the housing 160 and is provided with a coupling member adapted to cooperate with a companion member 168' (Fig. 15) on the main drive shaft 120. A bearing 167' carried on the housing 160 supports the shaft 166 adjacent its outer end.

The section of the shaft 166 adjacent the shaft 161 has a sleeve 169 splined thereon which constitutes the driven member of the clutch 121. A driving connection between the clutch members 165 and 169 is provided by a series of interleaved discs 170, drivingly connected alternately with

the member 165 and the member 169. To establish the driving connection, the discs are compressed between a collar 171 fixed on the sleeve 169 and a second collar 172 slidable on the sleeve. Shifting of the movable collar is effected by a clutch shifting member 173 slidably on the sleeve 169 and disposed in abutting relation to the collar 172.

Encircling the other section of the shaft 166 is an elongated sleeve member 180 supported in the housing 160 by anti-friction bearings 181 and 182. This sleeve member is arranged to be driven by a worm wheel 183 keyed thereon and a worm 184 fast on a shaft 185 which is connected with the output shaft of the hydraulic transmission H by a coupling 186 (Fig. 6).

The inner end of the sleeve 180 is formed with internal clutch teeth 187 adapted to be engaged by external teeth formed on a shiftable clutch member 188 splined to the shaft 166 intermediate the ends thereof. The clutch member 188 constitutes the driven member of the clutch 122 previously referred to.

The clutch members 173 and 185 are adapted to be shifted by a common actuator to drivingly couple either the rapid traverse motor M or the slow feed motor M' with the shaft 166 selectively or to disengage both clutches and thus interrupt rotation of the shaft. In the preferred form shown in Figs. 8 and 14, the clutch actuator is of the pressure fluid operated type and comprises a pair of cylinders 190 and 190' mounted in parallel relation upon a plate 191 adapted to be secured to one side wall of the housing 160. Pistons 192 and 192' working in the respective cylinders are connected by piston rods 193 and 193' to opposite ends of the yoke 194, which, in turn, is pivotally connected intermediate its ends to a rod 195 supported for axial shifting movement in a guide bearing 195 in the housing 160. Fixed on the rod 195 are a pair of clutch actuating fingers 196 and 197 engaging respectively in the peripheral grooves in the clutch members 173 and 188.

Introduction of pressure fluid into the inner ends of both cylinders 190 and 190' forces the associated pistons 192 and 192' to the extreme left position (as viewed in Fig. 14) thus shifting the rod 195 to the left. In this movement the rod 195 shifts the clutch member 173 to engaged position and at the same time withdraws the clutch member 188 to disengaged position. The rapid traverse motor M is therefore effective to drive the shaft 166.

Introduction of pressure fluid into the outer ends of both cylinders forces the pistons to their extreme positions in the opposite direction thereby engaging the driving and driven members of the clutch 122 and disengaging the clutch 121. Slow feed motor M' is then effective to drive the shaft 166 at a rate determined by the setting of the hydraulic transmission H. Introduction of fluid into the forward end of one cylinder and into the rear end of the companion cylinder shifts the pistons to the positions shown in Fig. 8 whereby the shifter rod 195 is moved to an intermediate position and both clutches are disengaged.

The feed selector unit B is mounted on the saddle 30 at the rear of the unit A and extends transversely across the saddle which is recessed as at 199 to accommodate the saddle traversing shafts as shown in Fig. 16. The unit includes a box like frame 200 having a series of transverse vertically disposed webs for supporting the inter-

mediate shaft 124 and the shafts 129 and 130. As will be seen, by reference to Fig. 16 the worm wheel 126 is keyed to the central portion of the shaft 124 and the shaft is provided at opposite ends with toothed members 201 and 202 constituting, respectively, the driving elements of clutches 121 and 128. The driven member of the clutch 121 comprises a sleeve 203 splined to the shaft 129 which is supported on the housing 200 in axial alignment with the shaft 124. Shaft 130 is also axially aligned with the shaft 124 and supported in suitable bearings carried on the housing 200. A sleeve member 204 splined to the shaft cooperates with the clutch member 202 and comprises the driven element of the clutch 128. Clutch members 203 and 204 are mechanically interconnected by a clutch shifting rod 205 (Figs. 8 and 15) having fingers 206^a and 207^a engaging in peripheral grooves in the respective clutch members. The clutch shifting rod is actuated in the same manner as the corresponding element of the actuator for the clutches 121 and 122. More particularly, a yoke 206 pivoted intermediate its ends on the rod 205 is connected at opposite ends by piston rods 207 and 207' with pistons 208 and 208' operating in parallel cylinders 209 and 209' attached to a side wall of the housing 200. By shifting these pistons individually or together, the clutches may be engaged selectively or set in a neutral disengaged position to interrupt the drive.

Disposed in the recess 199 in the saddle immediately below the selector unit B is a frame 210 adapted to support the shaft 136. Worm shafts 137 and 138 each journaled in separate frames 211 and 212 are coupled to opposite ends of the shaft 136 by means of couplers 213 and 214 of conventional type. Accurate alignment of the various shaft supporting frames is facilitated by the provision of keys 215 on each frame cooperating with a complementary keyway 216 in the bottom of the recess 199.

The manner in which the vertical pinion shafts 139 are supported in the saddle 30 will be readily seen by reference to Fig. 17 of the drawings. Thus, the saddle is formed with recesses 199' communicating with the recess 199 at one side of each of the worm shafts 137 and 138. An upstanding hub 217 within each recess 199' provides seats for spaced anti-friction bearings 218 for the shaft 139.

The machine elements enclosed in the units A and B above described and the saddle driving mechanism are protected from entry of dirt or other foreign material by means of suitable cover plates of sheet metal or the like. Thus, the housing for the unit A is closed at its upper end by a cover 218 (Fig. 14) while the frame structure of the unit B is closed by cover sections 219 and 219'. The unit B extends over and covers a substantial portion of the recess 199 while the section in which the frame 212 is located is closed by a cover plate 220. Suitable cover plates 221 encloses the recess 199' in which the pinion shafts 139 are located.

As mentioned hereinbefore, the drive for the table includes a reduction gear mechanism C interposed between the shaft 133 and the vertical table driving shaft 65. Referring to Fig. 18, it will be observed that the shaft 133 is connected by a coupling 222 with a horizontally disposed shaft 223 having a pinion 224 meshing with a pinion 225 on a parallel shaft 226. A bevel gear 227 fast on the shaft 226 engages a bevel gear 228 fast on a vertical shaft 229 which has a small

pinion 230 meshing with a large gear 231 on a companion vertical shaft 232. Shaft 232, in turn, has a small pinion 233 meshing with a large gear 234 on a vertical shaft 234'. The gear 234 also meshes with a gear 235 on a shaft 236 drivingly connected with the vertical shaft 65 by a suitable coupling 237. The various shafts are supported on anti-friction bearings on a housing 238 adapted to be bolted to the face of the saddle 30.

The hand feed unit D is operatively connected with the table drive shaft 65 through the speed reducing unit C by means of a bevel pinion 239 on the shaft 145 meshing with the bevel gear 228 on the shaft 229. As will be seen by reference to Fig. 6 of the drawings, the bevel pinions 227 and 239 are dimensioned so that each may mesh with the bevel gear 228 but do not mesh with each other.

Referring now to Figs. 7, 16 and 21, it will be observed that the speed regulating motor RM for the hydraulic transmission H is mounted on one side of the transmission within the sub-base 35 of the supporting structure. In order to provide a visual indication of the setting of the hydraulic transmission, a suitable dial type indicator 240 (Fig. 1) is provided on the hand feed unit E and operatively connected with the regulating motor. The connection, provided for this purpose includes a vertical shaft 241 (Fig. 16) drivingly connected with the transmission adjusting shaft by a bevel gear 242 and having at its lower end a spiral gear 243 arranged to drive a horizontal shaft 244. Shaft 244 extends into the housing of the unit E and has the indicator 240 attached to its projecting end within a recess 245 in the wall of the housing. This recess is closed by a transparent cover or window 245'.

The housing of the unit E is also formed to provide a compartment 246 immediately behind the indicator recess 245 for a pair of limit switches LS and LS' suitably interconnected with the regulating motor RM so as to limit the range through which it is permitted to turn the transmission adjusting shaft. These limit switches are adapted to be operated alternately by radially projecting switch operating fingers 247 and 248 fixed on the shaft 244 within the compartment 246. For convenience of access a switch S for starting and stopping the motor RM may be mounted on the housing of the unit E closely adjacent the indicator as shown in Fig. 1.

The hydraulic system for the clutch actuators and table and saddle clamps is shown diagrammatically in Fig. 8. Fluid such as oil is drawn from a sump or reservoir R through a filter F and delivered under pressure into a header 250 by a pump P which may be of any suitable type. A relief valve 251 connected with the header prevents excessive pressures from developing in the system. Pipes or ducts lead from the header to a series of conventional two-position control valves which direct the fluid to the cylinders of the various actuators. Thus, a valve 252 is operative to direct fluid to either end of the table clamping cylinder 91 while a valve 253 performs the same function with respect to the saddle clamping cylinder 91'. Valves 254 and 255 control the delivery of pressure fluid to cylinders 190 and 190' of the rapid traverse and feed clutch actuator. In a like manner valves 256 and 257 control the delivery of fluid to the cylinders 208 and 209' of the feed selector clutch actuator.

The control valves are preferably adapted to

be operated by solenoids so that their setting may be readily effected by remote control. Moreover the electrical circuits for the solenoids may be interlocked in well-known manner so that the operation of the actuators in the proper sequence is insured.

A pressure lubricating system is also provided for insuring adequate lubrication of all bearing surfaces in the work supporting structure. As shown in Fig. 8, a pump P' is arranged to draw lubricating fluid such as oil from a reservoir R' through a filter F' and deliver it under pressure through a duct 260 to a control valve 261. One branch line leading from the valve carries oil to the table supports 100. Another branch line delivers oil to the speed reduction gear unit C, the table driving worm 64, and the bearings of the table spindle 39. The latter branch is provided with a check valve 262 to prevent reverse flow of oil. Oil pressure in this system is controlled by a suitable relief valve 263.

A second pump P'' arranged to draw oil from the reservoir R' through a filter F'' delivers the fluid under pressure to a line 265 which has one branch leading to a valve 266 controlling the flow of fluid to the feed selector unit B and to the ways 31. Another branch of the line 265 extends through a check valve 267 to the feed and rapid traverse selector unit A. A relief valve 268 controls oil pressure in this system.

The valves 261 and 266 are preferably solenoid operated and their energizing circuits may be suitably interlocked with the circuits of the valves of the hydraulic system so that oil will be delivered to the proper machine elements when such elements require lubrication.

In the exemplary machine, the pumps P, P', and P'' are adapted to be driven by a common motor M''. The pumps and motor may be conveniently assembled as a unit on a frame 270 adapted to be bolted to one side of the saddle 30 as shown in Fig. 3. Suitable recesses in the saddle closely adjacent the pumps form the reservoirs R and R'.

It will be apparent from the foregoing that the invention provides a work support of novel and improved construction, particularly suitable for use with heavy duty machine tools such as horizontal boring, drilling and milling machines. The invention embodies in one unitary structure a rotatable work supporting table, a translatable carriage for the table and power means operable selectively to translate the carriage or to rotate the table at either a rapid traverse rate or a slower, variable feed rate. The improved work support may be installed in existing machines of the table type or may be supplied with an individual bed to adapt it for use with floor type boring, drilling and milling machines. The table supporting frame work, drive mechanism and other parts are all of sturdy construction and enable the supporting structure to be used with extremely large workpieces and for what is commonly known as heavy duty service. The various elements of the drive mechanism are constructed in the form of simple compact units to facilitate manufacture and initial assembly and likewise simplify the removal of such elements for replacement or repair.

The invention also provides novel means for positively clamping the movable elements of the supporting structure against undesired movement and means for supporting the peripheral edge of the rotary work table so as to prevent deflection of the table under load.

We claim as our invention:

1. A work support comprising, in combination, a carriage adapted to travel on horizontal ways, a frame rising from said carriage, a work supporting table rotatably mounted on said frame, driving mechanism operative to traverse the carriage on the ways, other driving mechanism operative to rotate the table, a rapid traverse motor, a slow feed motor, a main drive shaft, a clutch operative when engaged to drivingly connect the rapid traverse motor with said shaft, a second clutch operative when engaged to drivingly connect the slow feed motor with said shaft, a third clutch operative when engaged to drivingly connect said shaft with one of said driving mechanisms, a fourth clutch operative when engaged to drivingly connect said shaft with the other of said driving mechanisms, a remotely controlled power driven actuator for said first and second clutches, and a second remotely controlled actuator for said third and fourth clutches, said actuators being operable to engage the clutches selectively or to disengage all of the clutches.
2. A work support comprising, in combination, a carriage adapted to travel on horizontal ways, a frame secured to said carriage, a work supporting table rotatably mounted on said frame, driving mechanism operative to traverse the carriage on the ways, other driving mechanism operative to rotate the table, a rapid traverse motor, a slow feed motor, a main drive shaft, a clutch operative when engaged to drivingly connect the rapid traverse motor with said shaft, a second clutch operative when engaged to drivingly connect the slow feed motor with said shaft, a third clutch operative when engaged to drivingly connect said shaft with one of said driving mechanisms, a fourth clutch operative when engaged to drivingly connect said shaft with the other of said driving mechanisms, a pressure fluid operated actuator for said first and second clutches, a second pressure fluid operated actuator for said third and fourth clutches, and valve means for controlling the delivery of pressure fluid to said actuators.
3. A work support comprising, in combination, a carriage adapted to travel on horizontal ways, a frame secured to said carriage, a work supporting table rotatably mounted on said frame, driving mechanism operative to traverse the carriage on the ways, other driving mechanism operative to rotate the table, a rapid traverse motor, a slow feed motor, a main drive shaft, clutch means engageable selectively to connect either of said motors with said shaft, and other clutch means engageable selectively to connect said shaft with either of said drive mechanisms.
4. A work support comprising, in combination, a carriage adapted to travel on horizontal ways, a frame secured to said carriage, a work supporting table rotatably mounted on said frame, driving mechanism operative to traverse the carriage on the ways, other driving mechanism operative to rotate the table, a rapid traverse motor, a slow feed motor, and means operable to connect either of said motors with either of said driving mechanisms selectively.
5. A work support comprising, in combination, a carriage adapted to travel on horizontal ways, a column like frame rising from the carriage, a work supporting table rotatably mounted on said frame, driving mechanism operative to rotate the table, a rapid traverse motor on said carriage, a slow feed motor on said carriage, a clutch operative when engaged to connect said rapid
- traverse motor with said driving mechanism, a second clutch operative when engaged to connect said slow feed motor with said driving mechanism, and actuating mechanism common to said 5 clutches operable selectively to engage either clutch individually or to disengage both clutches.
6. A work support comprising, in combination, a carriage adapted to travel on horizontal ways, a frame secured to the carriage, a work supporting 10 table rotatably mounted on said frame, driving mechanism operative to rotate the table, a rapid traverse motor on said carriage, a slow feed motor on said carriage, a clutch operative when engaged to connect said rapid traverse motor with said driving mechanism, a second clutch operative when engaged to connect said slow feed motor with said driving mechanism, and actuating mechanism operable to engage and disengage 15 said clutches selectively.
7. A work support comprising, in combination, a carriage adapted to travel on horizontal ways, a frame secured to the carriage, a work supporting table rotatably mounted on said frame, driving mechanism operative to rotate the table, a rapid traverse motor on said carriage, a slow feed motor on said carriage, clutch means engageable 20 selectively to couple either motor to said drive mechanism, and remotely controlled power driving means for actuating said clutch means.
8. A work support comprising, in combination, a carriage adapted to travel on horizontal ways, a frame secured to the carriage, a work supporting table rotatably mounted on said frame, driving mechanism operative to rotate the table, a rapid traverse motor on said carriage, a slow feed motor on said carriage, and means operable 25 selectively to connect either motor to said drive mechanism.
9. A work support comprising, in combination, a carriage adapted to travel on horizontal ways, a column like frame rising from said carriage, a work supporting table mounted on said frame for rotative movement, and power drive means 30 including a prime mover operable selectively to traverse said carriage or to rotate said table, said carriage, said frame, said table and said power drive means being assembled to form a self-contained unitary structure.
10. The combination with a work supporting 35 table rotatably mounted on a stationary frame, means supporting the periphery of the table to prevent deflection under load comprising, a track on the rear face of the table concentric with its rotational axis, a shoe supported on the frame 40 in a position to engage said track, and means yieldably urging said shoe against the track.
11. The combination with a work supporting 45 table rotatably mounted on a stationary frame, means supporting the periphery of the table to prevent deflection under load comprising, a track on the rear face of the table concentric with its rotational axis, a shoe having a flat bearing surface, means on the frame supporting the shoe with the bearing surface positioned for engagement with said track, and spring means yieldably 50 urging the shoe against the track, said spring means being adjustable to regulate the pressure exerted by the shoe on the track.
12. The combination with a work supporting 55 table rotatably mounted on a stationary frame, means supporting the periphery of the table to prevent deflection under load comprising, a track on the rear face of the table concentric with its rotational axis, a shaft supported on the frame 60 to rock about an axis substantially parallel to

said track, an eccentric on said shaft, a shoe mounted on said eccentric in a position to engage said track, and means for rocking said shaft to force said shoe against the track.

13. The combination with a work supporting table rotatably mounted on a stationary frame, means supporting the periphery of the table to prevent deflection under load comprising, a track on the rear face of the table, a shaft supported on the frame to rock about an axis substantially parallel to said track, an eccentric on said shaft, a shoe mounted on said eccentric in a position to engage said track, spring means operative to rock said shaft to force the shoe against the track, said spring means being adjustable to regulate the pressure exerted by the shoe on the track.

14. The combination with a work supporting table rotatably mounted on a stationary frame, means supporting the periphery of the table to prevent deflection under load comprising, a track on the rear face of the table, a shaft supported on the frame to rock about an axis substantially parallel to said track, an eccentric on said shaft, a shoe mounted on said eccentric in a position to engage said track, a crank arm on said shaft, an axially slidabie bolt having a nut threaded thereon for engagement with the free end of said crank arm, and a spring urging said bolt in a direction effective to rock said shaft and force the shoe against the track, the tension of said spring being adjustable by rotation of said bolt relative to said nut whereby to vary the pressure exerted by the shoe on the track.

15. The combination with stationary and movable machine parts, of means for positively clamping one part to the other comprising, a toothed member rigidly supported on one machine part, a toothed member slidably supported on the other machine part for movement into or out of engagement with said stationary member, means yieldably urging said sliding member into engagement with the stationary member, and power actuated means operative to hold said sliding member in engaged position.

16. The combination with a pair of relatively movable machine parts, of means for positively clamping said parts together, said clamping means comprising a toothed rack fast on one of the machine parts, a clamping plate having teeth formed in one side edge for engagement with the teeth of said rack and having the adjacent side edges tapering gradually from said one edge, means on said other machine part supporting said plate for movement toward and from said rack, wedge members engageable with the tapered side edges of the clamping plate to hold the teeth thereof in tight meshing engagement with the rack teeth, and power actuated means operative to shift said wedge members into engagement with said plate.

17. A work support having, in combination, a frame, a work supporting table rotatably mounted on said frame, power actuated table driving means, and means for positively clamping said table in a fixed position, said clamping means comprising, a ring gear fixed to the table, a clamping plate having teeth along one side edge adapted for engagement with the teeth of said gear, means on the frame supporting said plate for sliding movement toward and from said gear, spring means yieldably urging said plate toward the gear, cam means operative to hold said plate in a retracted position against the action of said spring means, said cam means being shiftable to permit

the advance of said plate, and means actuated in response to the shifting of said cam means for holding the plate in advanced positions.

18. A work support having, in combination, a frame, a work supporting table rotatably mounted on said frame, power actuated table driving means, and means for positively clamping said table in a fixed position, said clamping means comprising, a ring gear fixed to the table, a clamping plate having teeth along one side edge adapted for engagement with the teeth of said gear, means on the frame supporting said plate for sliding movement toward and from said gear, spring means yieldably urging said plate toward the gear, cam means operative to hold said plate in a retracted position against the action of said spring means, said cam means being shiftable to permit the advance of said plate, wedge members disposed on opposite sides of said plate engageable therewith to hold the plate in advanced position, and means providing an operative connection between said wedge members and said cam means operative to force the wedge members against the plate in response to the shifting of said cam means.

19. The combination, with an elongated machine bed, of a carriage supported for movement longitudinally of the bed, power actuated carriage driving means, means for positively clamping said carriage to the bed comprising, a toothed rack rigidly secured to the bed, a clamping plate having teeth formed in one side edge for engagement with the teeth of said rack and having adjacent side edges tapering gradually from said one side edge, means on the carriage supporting said plate for movement toward and from said rack, wedge members engageable with the tapered side edges of said plate to hold the teeth thereof in tight meshing engagement with the rack teeth, and power actuated means operative to shift said wedge members into engagement with the clamping plate.

20. A work support comprising, in combination, a carriage adapted to travel on ways, a frame secured to said carriage, a work supporting table rotatably mounted on said frame, driving mechanism for rotating said table, a rapid traverse motor on the carriage, a slow feed motor on the carriage, a variable speed transmission driven by said slow feed motor, and clutch means engageable to connect either said rapid traverse motor or said transmission to said driving mechanism.

21. A work support comprising, in combination, a carriage adapted to travel on ways, a frame secured to said carriage, a work supporting table rotatably mounted on said frame, driving mechanism for rotating said table, a pair of electric motors on said carriage, a variable speed hydraulic transmission, clutch means operative to connect one of said motors directly to said driving mechanism, and other clutch means operative to connect the other of said motors to said driving mechanism through said transmission.

22. A work support comprising, in combination, a carriage adapted to travel on ways, a frame on said carriage, a work supporting table rotatably mounted on said frame, table rotating mechanism, a first motor on the carriage, a second motor on the carriage, selectively operable means for establishing a driving connection from either motor to said table rotating mechanism, a variable speed hydraulic transmission interposed in the driving connection from the one of said motors, and means for visually indicating the setting of said transmission.

23. A work support comprising, in combination, a carriage adapted to travel on ways, a frame on said carriage, a work supporting table rotatably mounted on said frame, driving mechanism for traversing the carriage on the ways, other driving mechanism for rotating the table, a pair of electric motors on the carriage, means operable selectively to establish a driving connection from either motor to either of said driving mechanisms, and manually operable means for driving either mechanism independently of said motors. 5

24. A work support comprising, in combination, a translatable carriage, a frame on said carriage, a work supporting table mounted on said frame for rotative movement, driving mechanism operable to traverse said carriage, other driving mechanism operable to rotate said table, a motor mounted on said carriage, clutch means adjustable from a neutral position in which said motor is disconnected from both of said driving mecha- 10 15 20

nisms to either of two operative positions to couple said motor with said driving mechanisms selectively, and power actuated means for operating said clutch means.

25. A work support comprising, in combination, a translatable carriage, a frame on said carriage, a work supporting table rotatably mounted on said frame, driving mechanism operable to traverse said carriage, other driving mechanism operable to rotate said table, a motor on said carriage, clutch means operable to couple said motor with either one of said driving mechanisms or to disconnect the motor from both mechanisms, and an auxiliary drive unit associated with each of said drive mechanisms operable manually for driving said carriage and said table when said clutch means is set to disconnect said motor from said drive mechanisms.
